SHOWER HEAD

Ralph E. Bletcher and Irving A. Ward, Los Angeles, Calif., assignors of twelve and one-half per cent to Ernest H. Bucknell, ten per cent to Ralph E. Bletcher, twelve and one-half per cent to Mable Bucknell, ten per cent to Pearl White Bletcher, twenty-five per cent to Marcia Bucknell Liston, ten per cent to James H. Bletcher, ten per cent to Hazel Bletcher Skinner, and ten per cent to F. K. Robertson (also known as Charlotte R. B. Robertson)

Application April 23, 1951, Serial No. 222,468

10 Claims. (Cl. 299—107)

1

This invention relates to a new and useful shower head.

The principal object of this invention is to convert a stream of relatively high velocity water into a shower of finely divided and relatively low velocity water suitable for use in a shower bath or the like.

It is a further object of this invention to provide a shower head which will produce a shower consisting principally of droplets of water as distinguished from streams or jets of water produced in the ordinary shower head.

Still a further object of this invention is to provide a shower head wherein the discharge spray has a major axis and a minor axis, thereby rendering the shower head particularly adaptable for use in a bathtub or other installation. This is accomplished by providing a discharge spray, a cross section of which is approximately elliptical in shape and wherein the major axis is substantially larger than the minor axis.

The preferred embodiment of this invention contemplates a housing provided with a restricted throat and a plug member adapted to be inserted into said throat, means forming water passages to form and direct converging streams of water to said housing below said restricted throat and means for discharging water from the housing after the converging streams of water have contacted each other.

Other objects and advantages of this invention will be readily apparent from the following description.

In the drawings:

Figure 1 is a side elevation of the shower head embodying this invention attached to the water supply pipe.

Figure 2 is a sectional view taken along the line 2—2 of Figure 1.

Figure 3 is a sectional view taken along the line 3—3 of Figure 2.

Figure 4 is a plan view taken along the line 4—4 of Figure 2.

Figure 5 is a sectional view taken along the line 5—5 of Figure 2.

Figure 6 is a side elevation in section of a modified form of this invention.

Figure 7 is a plan view taken along the line 7—7 of Figure 6.

The shower head is formed by a housing 10 which is preferably cylindrical externally and threaded as at 12 at its upper extremity to adapt the shower head to be screwed into the retaining nut 14 provided at the extremity of the water supply pipe 16 to which water is supplied under

2

pressure. A transverse web 18 is provided inside the housing 10 forming a restricted throat 20 and dividing the housing into an upper chamber 24 and a lower chamber 28. A plug valve 22 is inserted into the upper chamber 24, the lower extremity 26 of the plug valve 22 being adapted to fit into the restricted throat 20, thereby preventing the flow of water from the upper chamber 24 to the lower chamber 28.

10 To permit passage of water by the plug valve 22 and into the lower chamber 28, a pair of recesses are provided, either in the plug valve or in the web to form water passages. In this particular embodiment these water passages 30 and 32 are formed by recessing the web 18. Thus when the removable plug valve 26 is inserted into the upper chamber 24 so that it projects into the restricted throat 20, water will flow from pipe 16 into chamber 24 about the plug valve 22 and through the water passages 30 and 32 in the form of converging streams emptying into the lower chamber 28. For reasons hereinafter described, it is preferred that the streams of water discharged through passages 30 and 32 be directed towards one another and that these streams be of substantially the same volume and velocity. The same volume in these two streams is insured by providing ribs 34 formed in the wall of the upper chamber 24. These ribs are 15 preferably positioned so that one of them will fall on each side of the passages 30 and 32 and so that the ribs falling on each side of these passages are equally spaced from the adjacent passage. The plug valve 20 is provided, in this embodiment, with a lip 36 at its upper extremity. The diameter of the lip corresponds approximately to the diameter of the space formed between the ribs 34. This lip 36 functions to insure a central location of the plug 20 and an equal spacing from the inner wall of the housing 10 all about the periphery of the plug 20. Thus water entering the upper chamber 24 is directed 20 between the ribs 34 into the opposed water passages 30 and 32 in equal quantities.

25 The lower extremity of the plug valve 26 is tapered or beveled as at 38, this tapered portion projecting a substantial distance above the web 18 when the lower extremity of the plug valve 26 projects into the restricted throat 20. The web 18 is preferably beveled at its upper side to receive the tapered portion 38 of the plug valve and to provide a suitable seat for said plug valve.

30 The recesses in the web 18 forming water passages 30 and 32 are at an angle with respect to the 35 axis of the housing so that the bottom of the

recess provides a surface substantially parallel to the beveled portion 38 of the plug 26. These recesses should also be sufficiently deep to assure continuous flow from the chamber 24 through the passages 30 and 32 into the lower chamber 28. The water passages 30 and 32, in this embodiment, are positioned exactly opposite one another on opposed sides of the central axis of the shower head and are of the same size. Thus the streams of water passing through these grooves are directed by the passages 30 and 32 towards one another. These two streams meet at a point in the lower chamber 28, the two streams being of the same velocity and same volume. When the two streams of water meet they break each other up into drops of water, which drops are directed towards the side walls of the lower chamber 28 and are discharged from the shower head in a manner hereinafter to be described.

The discharge opening 42 is formed by side walls 44 and 46 and end walls 48 and 50 which extend from the web 18 to the discharge opening. The side walls 44 and 46 are substantially longer than the end walls 48 and 50, for a purpose hereinafter to be described, and these longer walls are substantially parallel to the water passages 30 and 32. Thus when the two converging streams of water discharged through water passages 30 and 32 meet, the water is deflected onto the side walls 44 and 46 and some of which water follows the surface of the side walls to the discharge opening 42; other particles of the water strike the side walls 44 and 46 and are deflected inwardly, thereby filling the discharge spray. As the water pressure in the pipe 16 is increased, the volume of water and the velocity of the streams are increased, the greater amount of water being deflected onto the side walls 44 and 46. The water tends to spread out all along the side walls 44 and 46, thereby enlarging the discharge shower, giving the discharge shower a major axis and a minor axis. As this film of water spreads outwardly on the side walls it approaches the end walls 48 and 50, thereby enlarging the discharge shower. At one water pressure the outer extremity of the films of water on the side walls will pass around the curved edges of the end walls 48 and 50 and will join with one another. This creates a considerable turbulence, which can be eliminated by ribs 52 and 54 which are formed in the end walls 48 and 50 adjacent the discharge opening 42. These ribs function to divert the sheets of water at their outer extremity into the central part of the discharge shower. It is readily apparent that the character of the discharge shower is substantially controlled by the relative lengths of the walls 44 and 46 and the end walls 48 and 50. By elongating the walls 44 and 46, the major axis of the discharge shower is increased; similarly by increasing the end walls 48 and 50 the minor axis of the discharge shower is increased.

Referring now to Figures 6 and 7, wherein a modified form of this invention is illustrated and wherein like parts are given the same numerical designation as in the principal embodiment, the only difference between the modified form and the principal embodiment lies in the provision of arcuate bevels formed in the side walls 44 and 46. These bevels 56 and 58 are preferably formed in the side walls 44 and 46 of chamber 28 at a position substantially above the discharge opening 42. The purpose of these bevels is to alter the shape of the discharge shower. Thus as the side walls 44 and 46 approach the circular shape of the

housing 10, due to these bevels, the more circular in form the discharge shower becomes.

The operation of these shower heads is as follows. Water is delivered at pressure through the supply pipe 16 to the upper chamber 24. The water then passes between the ribs 34 around the plug valve 26 and through the water passages 30 and 32. The two discharge streams are directed by the passages 30, 32 towards one another. When the two streams, which are of approximately the same volume and velocity meet, a large portion of the water is deflected onto side walls 44 and 46. The water then passes down the side walls and is discharged. As the water pressure is increased, the area of the side walls onto which the water is deflected increases and the discharge shower enlarged. By varying the depth of the water passages 30 and 32, the shower can be changed from a very fine mist, in the case of extremely shallow passages, to heavy drops, in the case of deep passages. However, the shower produced by this shower head is soft in character and does not produce streams or jets of water as does the conventional shower head.

The plug valve 22 is preferably removably retained in chamber 24 and foreign matter which collects in chamber 24 may be flushed by pushing the plug 22 upward.

While the above description is of the preferred embodiment of this invention, it is readily apparent that changes in the size, shape and formation of the elements can be resorted to without departing from the scope of the appended claims.

We claim:

1. A shower head comprising: a housing provided with a web forming a restricted throat, movable plug means to control flow through said throat held in said throat by the weight of the plug, converging water passages formed between said web and said plug means directing flow of water into the lower portion of said housing from which water is discharged in the form of a shower comprising a plurality of droplets of water similar to raindrops.

2. A shower head comprising: a housing provided with a web forming a restricted throat, movable plug means adapted to be inserted into said throat held in said throat by the weight of the plug, water passages formed between said web and said plug means to direct flow of water into streams which converge in the lower portion of the housing from which water is discharged in the form of a shower comprising a plurality of droplets of water similar to raindrops.

3. A shower head comprising: a housing provided with a web forming a restricted throat dividing said housing into upper and lower chambers, movable plug means adapted to be inserted into said throat held in said throat by the weight of the plug, means forming water passages between said web and said plug means, said water passages communicating between the upper and lower chambers of said housing and directing flow of water into streams which converge in the lower chamber of said housing from which water is discharged in the form of a shower comprising a plurality of droplets of water similar to raindrops.

4. A shower head comprising: a housing provided with a web forming a restricted throat dividing said housing into upper and lower chambers, plug means adapted to be inserted into said throat, means forming water passages between said web and said plug means, said water passages communicating between the

upper and lower chambers of said housing and directing flow of water into streams which converge in the lower chamber of said housing, and ribs in said upper chamber to center said plug means and direct an equal volume of water into each of said water passages.

5. A shower head comprising: a housing provided with a web forming a restricted throat dividing said housing into upper and lower chambers, plug means adapted to be inserted into said throat, means forming water passages between said web and said plug means, said water passages communicating between the upper and lower chambers of said housing and directing flow of water into streams which converge in the lower chamber of said housing, said lower chamber having side walls substantially parallel to said water passages which are substantially larger than the end walls of said chamber.

6. A shower head comprising: a housing provided with a web forming a restricted throat dividing said housing into upper and lower chambers, plug means adapted to be inserted into said throat, means forming water passages between said web and said plug means, said water passages communicating between the upper and lower chambers of said housing and directing flow of water into streams which converge in the lower chamber of said housing, said lower chamber having side walls substantially parallel to said water passages which are substantially larger than the end walls of said chamber, and ribs formed on each end wall of said lower chamber.

7. A shower head comprising: a housing provided with a web forming a restricted throat dividing said housing into upper and lower chambers, plug means adapted to be inserted into said throat, means forming water passages between said web and said plug means, said water passages communicating between the upper and lower chambers of said housing and directing flow of water into streams which converge in the lower chamber of said housing, and ribs in said upper chamber to center said plug means and direct an equal volume of water into each of said water passages, said lower chamber having side walls substantially parallel to said water passages which are substantially larger than the end walls of said chamber.

8. A shower head comprising: a housing provided with a web forming a restricted throat dividing said housing into upper and lower chambers, plug means adapted to be inserted

5 into said throat, means forming water passages between said web and said plug means, said water passages communicating between the upper and lower chambers of said housing and directing flow of water into streams which converge in the lower chamber of said housing, ribs in said upper chamber to center said plug means and direct an equal volume of water into each of said water passages, said lower chamber having side walls substantially parallel to said water passages which are substantially larger than the end walls of said chamber, and ribs formed on each end wall of said lower chamber.

10 9. A shower head comprising: a housing provided with a transverse web dividing said housing into upper and lower chambers, means forming water passages communicating between said upper and lower chambers, said water passages directing water into streams which converge in said lower chamber, said lower chamber having side walls substantially parallel to said water passages which are substantially longer than the end walls of said lower chamber.

15 10. A shower head comprising: a housing provided with a web forming a restricted throat dividing said housing into upper and lower chambers, plug means adapted to be inserted into said throat, means forming water passages between said web and said plug means, said water passages communicating between the upper and lower chambers of said housing and directing flow of water into streams which converge in the lower chamber of said housing, said lower chamber having side walls substantially parallel to said water passages which are substantially larger than the end walls of said chamber, said side walls of the lower chamber having arcuate bevels in the lower portion thereof.
